MECHANICAL MOVEMENT FOR COATING APPARATUS

Richard J. Verba, Fairview Park, Ohio, assignor, by mesne assignments, to Howard V. Schweitzer

Application April 2, 1954, Serial No. 420,702

4 Claims. (Cl. 118—315)

This invention relates to mechanism employed in coating large articles on a mass production basis and is particularly applicable to the coating of large bodies having irregular, curved surfaces, such as automobile bodies.

In recent years, machinery has been developed to automatically spray coat, on a production line basis, large objects or objects having surfaces of large expanse. Such machinery has been provided in order to reduce or eliminate the high labor costs and the health hazards involved in manual spray coating.

The machines which have heretofore been developed for these purposes share one common feature: great mechanical complexity. The general scheme of such machinery is the provision of linkages to move paint guns over the surfaces of the articles being coated in such a way as to maintain the paint guns substantially normal to and at a substantially constant distance from the surface. This is accomplished in a variety of ways, all involving costly custom fabrication of curved load-bearing beams, cable-powered drag-link drives, articulated conveyor track sections, complex cam linkages or other extremely expensive mechanical elements.

The present invention provides a mechanism which is far more simple and troublefree than those heretofore provided. This mechanism may be adapted to a variety of requirements of particular installations. The mechanism comprises a traversing assembly including an endless flexible drive means extending along a beam on which a carriage is mounted for reciprocating movement, the carriage being directly coupled to the endless drive means and the carriage also reciprocally mounting an additional member for transverse movement relative to the beam in the manner disclosed below. The versatility and adaptability of this mechanism will be illustrated in several illustrative embodiments of painting or coating installations in which it may be employed.

The objects and advantages of the mechanism will be most clearly understood from the following specification and the accompanying drawings in which:

Figure 1 illustrates a coating installation in which two different embodiments of the invention are employed.

Figure 2 is a rear elevation on an enlarged scale of the upper left portion of the mechanism illustrated in full-line in Figure 1.

Figure 3 is a view similar to Figure 2, but showing the parts in different positions.

Figure 4 illustrates a coating installation employing another embodiment of the invention.

Figure 5 is a plan view of Figure 4, a control valve (155) shown in Figure 4 being omitted from Figure 5 for purposes of clarity.

Figure 6 is a view taken on line 6—6 of Figure 5.

Figure 7 is a view on an enlarged scale taken on line 7—7 in Figure 5.

Figure 8 illustrates a coating installation employing still another embodiment of the invention.

2

Side coating mechanism of Figures 1—3

The mechanism contemplated by the invention is illustrated in Figure 1 in connection with an automobile body coating operation in which an overhead conveyor is employed. A vertical beam 10 is provided at the side of the conveyor line at the coating station. A horizontal beam 11 extends over the top of passing car bodies and is supported on the beam 10. As will become clear below, each of these beams functions as the major structural support for its associated reciprocating coating mechanism. Power is supplied through a power linkage comprising a motor 12, a flexible drive 13 and a standard speed reducer 14. The output side of the speed reducer 14 is drivingly engaged with the sprockets 15, 16, 17 and 18 in a manner which is clearly illustrated in Figure 1. The sprocket 15 comprises the power sprocket for the mechanism associated with the beam 11. The sprockets 16, 17 and 18 comprise the power sprockets for the mechanism associated with the beam 10.

A carriage 20 is mounted for reciprocation up and down the beam 10. The carriage preferably comprises a plate 21 cut to the shape indicated and provided with laterally extending flanged rollers 22, each of which is in guided engagement either with flanges of the beam 10 or, preferably, with flat rails or tracks 23 formed on the flanges of the beam 10. An additional set of double flange rollers 24 is provided on the opposite side of the plate 21 from the rollers 22. The rollers 24 are in guiding engagement with a reciprocating bar 25. Pivoted to the bar 25 is a following link 26, the pivotal movement of which is transmitted to a sister link 27 through a long link 28, as clearly shown in Figure 1. A follower on the end of the link 26 is in engagement with a cam bar 29. A follower on the end of the reciprocating bar 25 is in following engagement with the cam bar 30. The cam bars 29 and 30 are supported to one side of the beam 10 in any suitable manner.

A bar gun 31 is mounted on a shaft 32, which is operatively fixed with link 27 and rotatably mounted on the reciprocating bar 25. At a central portion of the plate 21, a slot track 34 is provided extending laterally beyond both reaches of a chain 35, which is engaged by the sprocket 18 and an additional idler sprocket 38. The chain 35 is provided with one link which embodies a drive bushing or lug 36, which is in driving engagement with the sides of the slot track 34.

It will be apparent that as the power sprocket 18 is actuated, engagement of the lug 36 with the plate 21 will cause the carriage 20 to reciprocate between the sprockets 18 and 38. During such reciprocating movement of the carriage, the bar 25 will be caused to reciprocate toward and away from the article being coated, following engagement between the bar 25 and the cam bar 30 being maintained by a spring 37 extending between the plate 21 and the bar 25. Thus, the in-and-out position of the paint gun 31 is determined by the conformation of the cam bar 30 and is a function of the vertical position of the carriage 20. The angle of tilt of the gun is determined by the included angle between the reciprocating bar 25 and the link 26. It will be seen that this is determined by the conformation of both the cam bars 29 and 30. This angle of tilt will also be a pre-determined function of the vertical position of the carriage 20.

Top coating mechanism of Figures 1—3

The linkage associated with the beam 11 is similar in general principle to that described above. A carriage 40 is provided comprising a plate 41 on which are mounted double flanged rollers 42, which are in driving engagement with the flanges of the beam 11, or, preferably, with flat bars 43 extending along the flanges of

the beam 11. An additional set of double flanged rollers 44 is provided on the carriage 40 on the opposite side of the plate 41 from the rollers 42. The rollers 44 are in guiding arrangement with a reciprocating bar 45.

At its upper end the reciprocating bar 45 is provided with a follower roller which is in following engagement with a cam bar 52. The reciprocating bar 45 has mounted thereon members 46 and 47 (see Figures 2 and 3) between which is mounted a hydraulic cylinder 48. The actuating arm 49 of the hydraulic cylinder extends through the member 47 and is fixed to a crank 50. A paint gun mounting shaft 51 is rotatably carried by the crank 50.

A lever 55 is pivotally carried by the plate 41 or by a suitable extension or ear 56. At the outer end of the lever 55 a cam follower is mounted for following engagement with a cam bar 57. A link 58 connects the lever 55 to a lever 59 which is keyed to a shaft 60 rotatably mounted on the plate 41. Also keyed to the shaft 60 is a sprocket 61. An arm 62 is rotatably mounted on the shaft 60. At its opposite end, the arm 62 rotatably carries a shaft 63 on which a second arm 64 is rotatably mounted. The arm 64 extends to the gun mounting shaft 51 which is rotatably received by the arm 64. Keyed to the shaft 63 is a pair of sprockets, only one of which can be seen in the drawings. Keyed to the gun mounting shaft is a sprocket 67. A chain 68 is engaged with the sprocket 61 and one of the sprockets on the shaft 63. Another chain 69 is engaged with the other of the sprockets on the shaft 63 and the sprocket 67.

The pin-and-slot driving connection for the carriage 40 is similar to that for the carriage 20. A chain 70 is engaged with the power sprocket 15 and an idler sprocket 71, rotatably mounted on the beam 11. One of the links of the chain 70 comprises a pin or lug 72 in driving engagement with a slot on the plate 41 or, equivalently, with side plates or flanges forming a slot or channel. In Figures 2 and 3, the lug 72 is shown in driving engagement with two flanges 74, a slot 75 being provided merely to accommodate the cap bolt on the lug 72.

It will be understood that the up-and-down position of a paint gun 76 carried on the shaft 51 is controlled by the cam 52, while the tilt of the gun is controlled by the cam 57. Further, it will be seen that the motions determined by the shape of these cams will be identical, regardless of the position of the actuating rod 49 of the hydraulic cylinder 48. That is, the up-and-down and tilting motions of the paint gun 76 remain the same functions of the reciprocation of the carriage 40 regardless of the position of the actuating rod 49, a change in this position serving merely to shift the datum of the up-and-down motion of the paint gun.

As shown in phantom in Figure 1, all the linkages above described may be duplicated on the opposite side of the conveyor line, thus enabling the entire top and both sides of passing bodies to be simultaneously coated.

The paint gun and its associated linkage 62-69 are shown in raised position in Figure 2, the actuating rod 49 being fully withdrawn. In Figure 3, an intermediate position of the paint gun and its associated linkage 62-69 is shown in solid line, and the fully extended position is indicated in phantom view. Extension and retraction of the cylinder 48 may be controlled by suitable manually operated hydraulic valves (not shown) or by a cam-operated valve which is engaged for actuation by suitable protrusions associated with each passing body to be painted. For example, a valve 77 may be provided having a cam-control element 78 designed to be engaged by the passing hangers 79 associated with the conveyor system. The foremost of each pair of hangers associated with each passing body engages the element 78 to advance this element a half-turn to reverse the valve 77 to "lowered" position and the trailing hanger associated with each passing body engages the element 78 to advance this element an additional half-turn to reverse

the valve 77 to its original "raised" position. An additional valve (not shown) adapted to be actuated similarly to the valve 77 may be provided to turn the paint guns 76 and 31 on and off, spacing between the hangers 79 being maintained substantially equal to the length of body to be coated. The valve 77 is placed along the outgoing side of the conveyor a sufficient distance from the painting station to allow roof surfaces to be painted before the valve 77 is contacted by leading hangers 79 to then cause the paint gun 76 to be lowered to paint the rear decks of the passing bodies. Painting of each particular body is completed upon contact of its trailing hanger with the on-and-off valve. The valve 77 is then contacted by the associated trailing hanger to cause the paint gun to be raised into position for coating the roof surfaces of the next succeeding body.

Coating mechanism of Figures 4-7

Figures 4-7 show an embodiment of the invention in which the required overhead clearance above the reciprocating carriage is reduced by locating the camming bars on a level with guide and support beam along which the carriage travels.

As shown in Figures 4 and 5, a motor 100 is coupled to a speed reducer 101 on the output side of which is provided a power sprocket 102. An endless chain 103 engages the power sprocket 102 and an idler sprocket 104. The support beam 110 extends between side columns 111 and supports the several elements described above.

A carriage 120 is provided similar to the carriages 20 and 40 and comprises a plate 121 and flanged rollers 122 and 123 on opposite sides of the plate. The rollers 122 are in guided engagement with tracks 124 formed on the flanges of the beam 110. The rollers 123 are in guiding engagement with a reciprocating bar 130 to which is fixed a laterally extending shaft 131. A follower bearing 132 is rotatably mounted near the inboard end of the shaft 131. A sleeve 133 is also independently rotatably carried on the shaft 131. A cam follower crank 134 and a paint gun bracket 135 are each fixed to the sleeve 133. A paint gun 140 is carried on the paint gun bracket 135. The follower bearing 132 is in following engagement with a cam bar or track 142 and the follower crank 134 is in following engagement with another cam bar or track 143. The tracks 142 and 143 may be suitably supported and braced by transverse underlying beams 147 and 148, respectively, together with supports 149.

The chain 103 is provided with a lug 145 similar to the lug 72 of the embodiment shown in Figures 1-3. As seen in Figures 5 and 7, the lug 145 is in driving engagement with sideplates or flanges 146, similar to the sideplates or flanges 74. It will be apparent that as the power sprocket 102 is actuated, engagement of the lug 145 with the flanges 146 will cause the carriage 120 to reciprocate between the sprockets 102 and 104. During such reciprocating movement, the bar 130 and the associated shaft 131 will be caused to move toward and away from the top of the article being coated. Thus, the in-and-out (up-and-down) position of the paint gun 140 is determined by the conformation of the cam bar 142 and is a function of the transverse position of the carriage 120. The angle of tilt of the paint gun is determined by the difference in level of the axis of the sleeve 133 and the axis of the follower roller on the outer end of the crank 134. It will be seen that this is determined by the conformation of both the cam bars 142 and 143. This angle of tilt will also be a pre-determined function of the transverse position of the carriage 20.

In the painting or coating installation shown in Figures 4-7, the bodies to be painted, for example automobile bodies, are carried past the painting station on a deck conveyor rather than an overhead conveyor, making it possible to provide a single reciprocating carriage to cover the entire width of the roof of each passing body.

For adjustment and changeover purposes, the height of the beam 110 above the deck may be made adjustable by the provision of adjustment bolts 150 carried on the beams 111 and bolt and slot connections 151 between the beams 111 and the beam 110.

When it is desired that the paint gun be shut off at the end of each end of the path of the carriage in order to minimize overspray, an appropriate control device may be provided. In the installation shown in Figures 4-7, a valve 155 is mounted on the carriage 120. The central arm 158 of this valve is shifted to "off" position by the cams 156 and 157 at opposite ends of the path of the carriage 120.

Coating mechanism of Figure 8

Figure 8 illustrates a painting installation for coating automobile hoods or similar objects and employing another embodiment of the invention. Here an overhead conveyor is provided on which are rotatably mounted the hanger shafts 210 which support the hoods or similar objects 211 to be coated. The conveyor is provided with a conventional means for intermittent advancement so that each array of hoods is held at the coating station for a given period of time. During such time a friction wheel 212 on each hanger shaft 210 is engaged by a power driven belt 215, causing the array of hoods to rotate.

The coating linkage comprises a beam 200 having tracks 201 formed on the flanges thereof. A carriage 220, similar to carriages 20, 40 and 120, comprises a plate 221 on opposite sides of which are mounted flanged rollers 222 and 223. The rollers 222 are in guided engagement with the tracks 201. The rollers 223 are in guiding engagement with a reciprocating bar 225. Mounted at one end of the reciprocating bar 225 is a double crank 230 which is keyed to a shaft 231 on which a sprocket 232 is fixed. At the other end of the reciprocating bar 225 a paint gun bracket 233 is keyed to a shaft 234 on which a sprocket 235 is fixed. A chain 236 extends between the sprockets 232 and 235 and is also guided by a guide roll 237. A paint gun 240 is mounted on the paint gun bracket 233.

The ends of the double crank arm 230 are in guided engagement with cam surfaces 242 and 243 formed in a cut-out on a plate 245. The double crank arm 230 is urged into following engagement with cam surfaces 242 by a suitable spring (not shown).

The carriage 220 has a slot track formed on the plate 221 and generally indicated at 250. The slot track is drivingly engaged by a lug 251 on a chain 252 extending between a power sprocket 254 and an idler sprocket 255. The power sprocket 254 is driven by a motor 256 through a speed reducer 257.

It will be apparent that as the carriage 220 is caused to reciprocate by the drive linkage 250-257, the bar 225 will be moved toward and away from the articles being coated while, at the same time, the gun mounting bracket is caused to tilt in a predetermined manner, both in-and-out and tilting movement being controlled by the interaction of both cam surfaces 242 and 243 with the following ends of the double crank 230. Thus, both in-and-out and tilting movement are predetermined functions of the position of the carriage 220 in its reciprocating path.

It will be understood that suitable cam and valve means (not shown) may be provided to turn the paint gun off at the ends of travel of the carriage 220 and during times when no articles are at the painting station.

The various embodiments of the invention described above demonstrate the versatility and adaptability of the herein-disclosed mechanism to a variety of coating and paint installations. While installations for coating hoods and automobile bodies have been specifically illustrated, the invention is obviously applicable to the coating of other large curved surfaces. The invention has, in fact, been successfully employed in the coating of a variety of large curved sheet metal surfaces. This broad applicability of the disclosed paint-gun actuating linkage is

to be particularly noted in view of the narrow and specialized uses of the structurally and mechanically complex paint-gun actuating linkages heretofore provided. The illustration of the several embodiments of the invention should make it clear that many details of the invention may be varied without departing from the essence of the invention. Accordingly, the scope of the invention is not to be limited to such details but is to be defined by the following claims.

10 It is to be understood that the terms "surface treating head" and "member" as used in the claims apply not only to air atomizing paint guns but also to any other suitable means for coating such as electrostatic spray heads and to other means for surface treatment such as sand blasting heads, steam cleaning heads, polishing heads and scrubbing heads.

What is claimed is:

1. A device in which a surface treating head is to be moved across irregularly curved surfaces of passing objects and is to be maintained substantially normal to and at a substantially uniform distance from such surfaces, comprising a surface treating head, a carriage, a supporting beam extending substantially at right angles to but off-set from the path of passing objects, means for reciprocating the carriage along the supporting beam, fixed cam means extending along the direction of the supporting beam, control linkage means carried on said carriage and in following engagement with said fixed cam means, said control linkage means being operatively connected to the surface treating head to control the pivoting and reciprocating movements of the surface treating head relative to the carriage, the pivoting and reciprocating movements of the surface treating head each being a certain function of the reciprocating movement of the carriage along the supporting beam, a multiple-element structure included in said control linkage means, said multiple-element structure being movably mounted on the carriage so that the multiple-element structure can reciprocate to and from a datum position, moving substantially at right angles to the supporting beam, the surface treating head being pivotally connected to the multiple-element structure, and expansion means forming part of the multiple-element structure for varying the effective length of the multiple-element structure to change the datum position of the surface treating head without changing the datum position of the multiple-element structure and without causing either of said certain functions to cease to obtain.

2. A mechanical movement for translating a member along a first direction while simultaneously moving said member in and out along a second direction substantially normal to said first direction and tilting said member back and forth, said in-and-out and back-and-forth motions being predetermined functions of motion of said member along said first direction and said predetermined functions remaining the same regardless of a shift in the datum of said in and out motion, comprising a beam extending along said first direction, a carriage mounted for reciprocation along said beam and in guided engagement therewith, cooperating means on said carriage and said beam for effecting said guided engagement, drive means extending along said beam and drivingly engaging said carriage, power means to actuate said drive means, fixed cam surfaces extending alongside said beam, at least two followers engaged with different ones of said cam surfaces, a first control linkage comprising a reciprocator mounted on said carriage for reciprocation across said carriage in and out along said second direction, said reciprocator comprising a first portion, a second portion and a second power means operatively connected between said first and second portions for moving them relatively one to the other to thereby expand or contract the effective length of said reciprocator to two opposite limits, said initially recited member being pivotally mounted on

said second portion of said reciprocator, a second control linkage comprising a tilt-angle control linkage operatively connected to said initially recited member for transmitting angular motion thereto, said first and second control linkages being mechanically coupled to said cam followers to be actuated thereby, said second tilt-angle control linkage comprising means for imposing therethrough on said initially recited member a back-and-forth tilting motion which is said predetermined function of motion of said member along said first direction and remains the selfsame function independently of which of said two opposite limits obtains, whereby upon actuation of said first power means said member will be translated along said first direction and simultaneously will be moved in and out along said second direction and tilted back and forth, said in-and-out and back-and-forth motions being said predetermined functions of translation of said member along said first direction, and upon actuation of said second power means, said in-and-out and back-and-forth motions will continue as the same functions of translatory motion along said first direction but said in-and-out motion will occur with respect to a datum displaced along said second direction from the initial datum with respect to which said in-and-out motion occurred.

3. A mechanical movement for translating a member along a first direction while simultaneously moving said member in and out along a second direction substantially normal to said first direction and tilting said member back and forth, said in-and-out and back-and-forth motions being predetermined functions of motion of said member along said first direction, comprising a beam extending along said first direction, a carriage mounted for reciprocation along said beam and in guided engagement therewith, cooperating means on said carriage and said beam to effect said guided engagement, drive means extending along said beam and drivingly engaging said carriage, power means to actuate said drive means, a reciprocator mounted on said carriage for reciprocation across said carriage in and out along said second direction, means on said carriage guidingly engaging said reciprocator to guide said reciprocator in said in-and-out motion across said carriage, cam surfaces extending along said beam, first follower means on said reciprocator and in following engagement with one of said cam surfaces, said initially recited member being pivotally mounted on said reciprocator, a tilt-angle control linkage operably connected to said member and having second follower means in following engagement with another of said

cam surfaces, said tilt-angle control linkage comprising means for controlling the tilt-angle of said member responsive only to the conformation of said other of said cam surfaces, whereby upon actuation of said first power means said member will be translated along said first direction and simultaneously will be moved in and out along said second direction and tilted back and forth, said in-and-out and back-and-forth motions being predetermined independent functions of translation of said member along said first direction.

4. A device in which a paint gun is to be moved across irregularly curved surfaces of passing objects and is to be maintained substantially normal to and at a substantially uniform distance from such surfaces, comprising a paint gun, a carriage, a supporting beam extending substantially at right angles to but above the path of passing objects, means for reciprocating the carriage along the supporting beam, fixed cam means extending along the direction of the supporting beam, control linkage means carried on said carriage and in following engagement with said fixed cam means, said control linkage means being operatively connected to the paint gun to control the pivoting and reciprocating movements of the paint gun relative to the carriage, the pivoting and reciprocating movements of the paint gun each being a certain function of the reciprocating movement of the carriage along the supporting beam, a multiple-element structure included in said control linkage means, said multiple-element structure being movably mounted on the carriage so that the multiple-element structure can reciprocate to and from a datum position, moving substantially at right angles to the supporting beam, the paint gun being pivotally connected to the multiple-element structure, and expansion means forming part of the multiple-element structure for varying the effective length of the multiple-element structure to change the datum position of the paint gun without changing the datum position of the multiple-element structure and without causing either of said certain functions to cease to obtain.
